UNITED STATES PATENT OFFICE

FREDERICK STRATTNER OREM, OF BALTIMORE, MARYLAND

AIR CLEANER

Application filed November 25, 1929. Serial No 409,626.

My present invention relates to improvements in air cleaners, and more particularly it relates to air cleaners for supplying clean air to the carburetors of internal combustion engines.

One object of the invention is to provide a device for efficiently removing all dust at all speeds of the engine, since an internal combustion engine when operated in an automobile becomes a variable speed motor. This being so it is desirable to employ an air cleaner for supplying clean air to the carburetor, which will maintain its maximum cleaning efficiency at all speeds of the motor.

This is one of the principal objects of the device.

Another object is to provide an efficient air cleaner which while functioning to effectively remove all dust from the air at all speeds of the engine, will in no way retard or interfere under any condition with the free flow of air from the atmosphere to the carburetor.

A further object is the provision of an air cleaner which requires no attention and which is free from noise during operation and which muffles the noise produced by the carburetor.

Other objects will appear hereinafter from the accompanying description, claims, and drawing.

The invention consists in the features, combination, and arrangement of parts hereinafter described and particularly pointed out in the claims.

Referring to the accompanying drawing which shows one embodiment of my invention,

Figure 1 is a longitudinal sectional elevation of my improved air cleaner disposed in horizontal position for connection to the carburetor or intake of an engine.

Figure 2 is a section on line 2—2 of Figure 1.

Figure 3 is an end view of the cleaner.

Figure 4 is an end view of the end collar

on the eccentrically disposed outer tubular filter member, having an opening to receive a filter member of smaller diameter which is concentric or co-axial with the outer casing.

Figure 5 is an end view of the end collar on the innermost filter member having an opening in which is to be removably fitted the air outlet tube connected to the intake of the carburetor.

In the drawing, A represents the cylindrical outer casing of my device which is shown in position with its axis horizontal. Owing to the location of the carburetor on some internal combustion engines, it is more convenient to use a horizontal type of air cleaner. While the cleaner of my present invention is shown and intended to be used in a horizontal position, it will function in any position.

As shown, the tubular or cylindrical portion of the outer casing A is closed at its ends by head or cap members a and b having annular flanges a' and b' encircling the tubular housing. The tubular housing portion of casing A is provided preferably at its lower side with a longitudinal opening or slot c providing a dust laden air inlet.

The cap or head member a is also provided with a concentric flange d providing a central circular opening e through the head. Mounted in the circular opening e and secured to the head by any suitable means is a tube or cylinder C which is adapted to be connected with the intake of the carburetor and through which the air must pass in leaving the cleaner.

In the construction shown the tube C is fastened in place in the head a by means of a cotter pin or bolt f passing through aligned holes g in the tube C and flange d of the head a. The pin f passes through an eye h in the rod j which extends through the cleaner from one end to the other and is secured in the outside of the closed head b of the casing A by a nut k received on its threaded end l.

The tubular cylinder C is provided prefer-

- ably at its upper side with a longitudinal opening or slot m through which air is to pass on its way to the carburetor. The cylinder C extends to a point slightly spaced or removed from the closed head b and is preferably open at the end so that air may enter through the open end after passing through the narrow space o between the end of the cylinder and the closed head b . The hole of the cylinder C is of uniform diameter throughout to provide for free and unobstructed passage of the clean air there-through.
- The tube C is co-axial with the casing A .
- 15 Co-axial with the tube C is an inner tubular filter unit B which encloses it. This filter unit preferably composes a rectangular section of wire screening K covered with filter material and formed or rolled into substantially tubular shape, but with its opposed edges spaced apart to provide a longitudinal opening or slot R in the filter, and retained in such position by retaining cap members M and N of metal or the like placed over the ends of the tubular filter. The opposed edges of the screen covered with filter material are preferably provided with beads or clips O of metal or the like which serves as finishing and longitudinal stiffening or reinforcing strips as well as means for securing the filter material to the wire screen strips. Split spring bands P are placed within the screen at its ends to stress it against the filter material and into engagement with the retaining caps M and N .
- The filter unit B is provided at the outlet end of the casing with the retaining cap M , shown in Figure 5, having an opening to receive the tube C .
- 40 The other end of the filter B is provided with closed retainer cap N having an opening through which the tie rod extends. The filter is preferably disposed as shown with the slot R at its lower side.
- 45 The casing K , filter B , and tube C are all mutually co-axial and the annular spaces between them are of uniform size circumferentially.
- 50 In the annular space between the casing A and filter B is disposed another tubular filter member D the longitudinal axis of which is displaced with respect to the mutual axis of A , B , and C . This offset axis of tubular filter member D causes the eccentric arrangement shown in Figures 1 and 2 in which the lower side of filter D is spaced upwardly away from the lower side of the casing A and the upper side of filter D is spaced upwardly away from the upper side of filter B . This provides an outer annular eccentric or tapered passageway F , widest at its lower side at inlet opening c in casing A and tapering upwardly on either side to its most restricted portion at its upper side at slot n in filter D . This also provides an inner annular eccentric
- passageway E tapering downwardly on either side from slot n to its most restricted portion at its lower side at slot R in filter B .
- The filter D is constructed similarly to filter B of wire screening K' covered with filtering material L' and formed in substantially tubular shape with its edges spaced apart to provide slot n and retained in such condition by retaining cap members M' and N' of metal or the like placed over the ends of the tubular filter D . Beads or clips O' are also provided to cover the opposed longitudinal edges of the filter at the slot n , and springs bands P' are provided, similar to the construction of inner filter B . The retaining cap member M' of filter D as shown in Figure 4, is provided with an opening to receive the filter B with its cap M fitting snugly in said opening. The retaining cap member N' on the opposite end of filter D is closed except for the opening through which the tie rod extends. Cap member N' of filter D engages the inner face of head b and the cap member N of filter B in turn engages the inner face of cap member N' , as clearly shown in Figure 1.
- The cap member M' of filter D is preferably provided at its upper portion with a threaded hole p to receive a retaining screw r passing through a registering hole in head a to secure the parts together. Likewise the cap member M of filter B is provided at its lower portion with a screw threaded opening s to receive a securing screw t passing through the head a .
- In the operation of my device, the dust laden air enters the cleaner through opening c in the outer tubular casing A to eccentric annular passage F and passes through filter D to eccentric annular passage E . Air will also pass through opening n to passage E , filter D acting as a baffle.
- The air in passage E will then pass through filter B to annular passage H to and through opening m . Air will also pass from passage E through opening R to annular space H , filter B acting as a baffle. The air in space H passes through opening m into tube C and to the carburetor. Some air may pass into the open end of tube C through opening o .
- The filter units D and B , each comprising the wire net supporting a covering of filtering material, function both as filters and as baffles so that there is no interference under any condition with the free flow of air from the atmosphere to the carburetor.
- Casing A , filter B , and tube C are co-axial and concentric while D is eccentrically mounted with its axis offset which makes the inner and outer passages E and F eccentric or tapered, the object being to increase the velocity of air passing from opening c through passage F to opening n , and from opening n through passage E to opening R .
- Passages E and F each in effect comprises a pair of tapering passages having separate

5 circuitous paths, each pair having the same point removed from the air inlet in the cas-
inlet and outlet, and each passage being ing.
larger at its inlet and gradually tapering to
its smallest portion at its outlet. By this
construction the velocity of the air is in-
creased as it passes from the wider portion
of the passage to a narrow or restricted por-
tion.

10 The resistance offered to the flow of air by
reason of the tapered passages, while not suf-
ficient to interfere with the free flow of air
to the carburetor under any and all condi-
tions, has a tendency to induce the air to pass
directly through filters D and B instead of
15 through said continuous tapered passages
and openings, the air taking the path of least
resistance.

When the engine is running at high speed
20 with the throttle wide open, the continuous
tapered passageways will serve as an auxil-
iary passageway for the air, and the circui-
tous path traveled by the air baffled by the
filters will effectively clean the same.

25 The unitary construction of the parts as
shown in the drawing, and the simplicity of
construction provides for ready assembling
of the device.

30 Any number of filters could be added to
this cleaner without departing from my in-
vention and carrying out the principle ex-
emplified by the structure herein shown and
described as constituting one embodiment of
my invention.

35 I do not desire to limit the invention to the
exact structure disclosed as it will be appar-
ent that many modifications may be made
therein within the scope of the invention.

40 I do not desire to limit the invention to the
particular material of which the filters may
be constructed. Any kind of filtering mate-
rial may be used such as felt, flannel, mineral
wool or any porous material including por-
ous asbestos.

45 I do not desire to limit the invention to
the space between the inner filter and the
air outlet tube being of uniform size annu-
larly since this passage could be made taper-
ing. This could readily be accomplished in
50 the embodiment shown by the interposition
in said space of another eccentrically dis-
posed filter having its axis spaced from the
axis of the co-axial outlet tube and filter.

Having described my invention what I
claim is:—

55 1. In an air cleaner, a substantially tubu-
lar casing having an air inlet opening in its
wall, an air outlet tube centrally disposed
within and co-axial with said casing and hav-
ing an opening in its wall for the passage of
60 air, and a substantially tubular filter unit
disposed in the space between the casing and
tube and having its axis offset with respect
to the axis of the casing, said tubular filter
unit having an air passage in its wall at a

70 point removed from the air inlet in the cas-
ing.
2. In an air cleaner, a substantially tubu-
lar casing having an air inlet opening in its
wall, a substantially tubular filter unit dis-
posed within the casing with its axis spaced
from the axis of the casing and having an
air passage in its wall at a point remote from
the air inlet in the casing, the interior of said
filter unit communicating with an air outlet
75 in one end of the casing.

3. In an air cleaner, a substantially tubu-
lar casing having an air inlet opening in its
wall, a substantially tubular filter unit per-
80 vious to air disposed within the casing and
having an air passage in its wall at a point re-
mote from the air inlet in the casing, the in-
terior of said filter unit communicating with
an air outlet in the end of the casing.

4. An air cleaner according to claim 3 in
which the space between the walls of said
casing and filter unit is greater at the cas-
ing inlet opening and less at the air passage
in the wall of the filter.

5. An air cleaner according to claim 1 in
which the space between the walls of said
casing and filter unit is greater at the casing
inlet and less than at the air passage in the
filter wall and in which the space between the
walls of the filter and tube is greater at the
air passage in the filter wall and less at the
opposite side of the tube.

6. An air cleaner according to claim 3 in-
cluding an air outlet tube extending through
the end of the casing, said tube having an
air passage in its wall, the space between the
walls of said casing and filter unit being
greater at the casing inlet and less at the air
passage in the filter wall and the space be-
tween the wall of the filter and tube being
105 greater at the air passage in the filter wall
and less at the opposite side of the tube, each
space tapering between these points on either
side.

7. An air cleaner comprising a casing of
110 substantially tubular form having substan-
tially tubular members including filter
means, said tubular members nesting within
the said casing in spaced relation, said cas-
ing having a lateral inlet opening and said
115 tubular members each having a lateral inlet
opening, said lateral inlet openings being in
substantial diametrical alignment and being
disposed alternately and successively in the
walls of said casing and of said tubular
120 members on their opposite sides, and an air
outlet from the innermost tubular member
through the end of the casing.

8. An air cleaner according to claim 7
in which the annular spaces between said
125 nested substantially tubular members com-
municate successively at the laterally oppo-
site openings to form a continuous passage
from the inlet to the outlet of the casing, one
or more of said series of annular spaces being
130

wider at its inlet side than at its outlet side.

9. An air cleaner according to claim 7 in which one or more of said tubular casing and nested tubular members has its axis offset or spaced from the axis of another.

10. A filter unit for an air cleaner comprising filter material in substantially tubular form having cap members with flanges overlying its ends, and having a lateral inlet opening through its tubular wall, said opening comprising a slot extending longitudinally substantially throughout the length of the tubular wall.

11. A filter unit for an air cleaner comprising a sheet of filter material in substantially tubular form but with its opposed edges in spaced apart relation to provide a lateral inlet opening in its tubular wall in the form of a slot extending longitudinally throughout the length of the filter wall, and means for holding said filter material in such position.

12. A filter unit for an air cleaner according to claim 11 in which the opposed edges of said filter material forming the slot are each provided with a reinforcing and finishing bead, said means for holding the filter material comprising end cap members having flanges overlying the filter material, and split spring retaining rings within the tubular filter material and urging it into engagement with the flanges of the cap members, said filter material comprising a sheet of wire net or screening supporting a covering of filtering medium.

13. An air cleaner comprising a substantially tubular casing having a longitudinal air inlet slot in its tubular wall and having a closed end wall and an end wall having a central opening, an air outlet tube disposed within the casing and extending through said central opening, said tube having a longitudinal slot in its tubular wall, a substantially tubular filter unit disposed in the space between the casing and tube and having its axis offset with respect to the axis of the casing, said tubular filter unit having a longitudinal slot in its tubular wall at the side laterally opposite to the air inlet in the casing.

14. An air cleaner according to claim 13 in which said filter unit comprises a sheet of filter material in tube form and having a closed cap member at the closed end of the casing and a cap member at the opposite end having an opening to receive the tube.

15. An air cleaner according to claim 13 in which an inner filter unit is disposed between said tube and eccentrically disposed filter unit, said inner filter unit being co-axial with the tube and casing and having a longitudinal slot in its tubular wall at the side laterally opposite the slots in the eccentrically disposed filter unit and the said tube, said filter units each comprising a sheet of filter ma-

terial in tube form and having a closed cap member at the closed end of the casing and a cap member at the opposite end having an opening, whereby said casing filter units and tube are disposed one within another in nesting relation.

16. An air cleaner according to claim 13 in which said tube is open at both ends, its inner open end being spaced slightly from the closed end of the air cleaner to provide an auxiliary air outlet opening.

17. An air cleaner comprising a casing of substantially tubular form having a lateral inlet, means within said casing forming a plurality of annularly disposed air passages disposed one within another and communicating successively at laterally opposite points to form a continuous passage from the said lateral inlet to a substantially central outlet in the end of the casing, and one or more of said passages being wider at its inlet and narrower at its outlet.

18. A filter unit for an air cleaner comprising a substantially tubular filter having a lateral inlet opening through its tubular wall, said opening comprising a slot extending longitudinally throughout substantially the length of said filter wall for the passage of air through said slot substantially from end to end of said filter wall, said filter unit having an outlet opening in its end.

19. In an air cleaner, a casing having an air inlet opening and an air outlet opening, and a hollow filter element pervious to air located in the casing between the inlet and outlet openings thereof, the filter element having an air inlet opening remote from the inlet opening of the casing and said element communicating interiorly with the outlet opening of the casing, and the casing and filter element having therebetween a passageway extending from the inlet opening of the casing to the inlet opening of the filter element and decreasing in size in the direction of the inlet opening of the filter element.

20. In an air cleaner, a casing having an air inlet opening and an air outlet opening, hollow filter elements pervious to air, located one within the other and within the casing between the inlet and outlet openings thereof, the outermost filter element having an air inlet opening remote from the inlet opening of the casing, the innermost filter element communicating interiorly with the outlet opening of the casing and having an air inlet opening remote from the inlet opening of the outermost filter element, the casing and outermost filter element having therebetween a passageway extending from the inlet opening of the casing to the inlet opening of this filter element and decreasing in size in the direction of the inlet opening of this filter element, and the innermost and outermost filter elements having therebetween a passageway extending from the inlet opening of the outermost ele-

ment to the inlet opening of the innermost element and decreasing in size in the direction of said last inlet opening.

21. In an air cleaner according to claim 20, a hollow member in and spaced from the innermost filter element, said hollow member having an air inlet opening communicating with the interior of the innermost filter element and remote from the inlet opening of such element, said hollow member constituting the air outlet of the filter.

In testimony whereof, I affix my signature.
